UNITED STATES PATENT OFFICE.

EDWIN ALLEN, OF MOUNT VERNON, NEW YORK, AND GEORGE W. CARVER, OF BROOKLINE, MASSACHUSETTS, ASSIGNORS TO JOHN W. GREENE AND WILLARD H. PLATT, OF BROOKLYN, NEW YORK, COMPOSING FIRM OF GREENE, TWEED & COMPANY, OF NEW YORK, N. Y.

LUBRICATOR.

SPECIFICATION forming part of Letters Patent No. 731,833, dated June 23, 1903.

Application filed May 24, 1902. Serial No. 108,855. (No model.)

To all whom it may concern:

Be it known that we, EDWIN ALLEN, residing at Mount Vernon, Westchester county, New York, and GEORGE WALLACE CARVER, residing at Brookline, Norfolk county, Massachusetts, citizens of the United States, have invented certain new and useful Improvements in Lubricators, of which the following is a specification.

10 Our invention relates to improvements in force-feed lubricators; and the object of the invention is to provide a simple, compact, and durable device especially adapted for motor-vehicles and one which may be produced at an extremely low cost.

15 The invention is illustrated in the accompanying drawings, in which—

Figure 1 is a front elevation. Fig. 2 is a side view. Fig. 3 is a horizontal section. Fig. 4 is

20 a central vertical section.

In the various figures similar reference-letters designate the same or like parts.

The oil reservoir or chamber is shown at A and is preferably of the shape shown, with a 25 flattened front to carry the working parts, as hereinafter described. It is preferably formed by casting and is provided with base flanges or lugs a, having bolt or screw holes whereby the reservoir may be secured to any 30 desired part. The open upper end of the reservoir is closed by a suitable cap A', an oil-strainer A² of any desired construction being provided beneath the cap.

The flat front wall of the reservoir is preferably cast with thicker portions B at the corners, which are bored out to form chambers, one a piston chamber or cylinder C and the other a valve-chamber D. The lower end of the piston-chamber is provided with narrow 35 borings to form valve-seats for the reception of ball-valves, as indicated at the lower right-hand corner of Fig. 1 in dotted lines.

Above the upper valve is a transverse passage E, which communicates with the valve-chamber D, this passage being preferably extended through to the outside of the reservoir and closed by a screw cap or plug e.

Below the lower valve the piston-chamber communicates with the interior of the reservoir.

The valve-chamber D is provided with similar valve-seats and valves, as indicated at the left of Fig. 1 in dotted lines, and an oil-delivery pipe D' is tapped into the upper end of the chamber, by which the oil may be conveyed to the parts to be lubricated.

Within the piston-chamber is located a piston F, which is operated by a vertically-moving slide G, guided in a way or groove formed in the front face of the reservoir. This slide carries an arm g at its upper end which enters a slot in the piston. A set-screw f in the upper end of the piston provides means for adjusting or varying the lost motion, and a clamp-nut f' is provided for locking the screw in any desired position.

The slide is operated to impart movement to the piston by a cam H, journaled upon a shaft I, having its end threaded through the front wall of the reservoir and locked in place by a nut i. An elongated slot in the slide permits movement of the slide with relation to the pin which passes through the slide. Shoulders g' and g'' are provided on the slide above and below the cam, which coact with the cam as it rotates to effect the vertical movement of the slide.

In order to rotate the cam, a ratchet-wheel K is rigidly connected thereto, preferably by mounting it on a reduced extension, as shown. A hub L is journaled on the shaft, which has an arm L' extending outward slightly beyond the periphery of the ratchet-wheel, where it is provided with a pawl l', engaging the ratchet-teeth.

An arm L² is adjustably secured to the hub L by a set-screw l² and is designed to be operated from a suitable part of the automobile. From the manner in which this arm is mounted it will be seen that it may be adjusted to any desired position, and thus adapted for connection to any style of automobile.

A pawl l⁴, pivoted to a bracket l⁵, carried by the reservoir, holds the ratchet-wheel against

ovement during the backward movement of the movable pawl.

Having thus described our invention, what we claim is—

1. In a force-feed lubricator the combination with the reservoir having a flat side wall with a suitable piston-chamber extending downward from its upper edge and an exit-passage, a piston in said chamber, a slide guided by said wall, a spindle mounted in the wall of the reservoir and projecting through an elongated opening in the slide, and means carried by the spindle for transmitting the motion of the prime mover to the slide, and a connection between the slide and piston-rod, substantially as described.

2. A force-feed lubricator comprising a reservoir having a suitably-thickened wall, a vertical piston-chamber in said wall at one side communicating with said reservoir, a vertical delivery-chamber in said wall on the opposite side having a communication at its lower end with the piston-chamber, valves in said chambers, a slide working in a groove in said wall centrally of said chambers, a piston in the piston-chamber having a variable connection with said slide, a spindle carried by said wall and projecting through an elongated opening

in the slide, a cam journaled on the spindle, ribs on the slide embracing said cam, and a pawl-and-ratchet mechanism for operating said cam from the prime mover, substantially as described.

3. In a force-feed lubricator the combination with the reservoir having a suitable piston-chamber and exit-passage, of a slide guided in the wall of said reservoir, a spindle having one end rigidly secured to said wall and projecting through an elongated opening in the slide, a cam rotatably mounted on said spindle and bearing against oppositely-located ribs on the slide, a piston in the piston-chamber operatively connected with the slide, a ratchet-wheel rigidly connected with the cam, an arm rotatably mounted on the shaft and carrying a pawl engaging the teeth of the ratchet-wheel, and a second arm adjustably connected to said first-named arm, substantially as described.

In testimony whereof we affix our signatures in presence of two witnesses.

EDWIN ALLEN.

GEORGE W. CARVER.
